UNITED STATES PATENT OFFICE

CHARLES T. READ, OF MILWAUKEE, WISCONSIN

EXTERNAL SHANK SUPPORTER

Application filed November 8, 1929. Serial No. 405,712.

This invention relates to improvements in arch supporters.

One of the objects of my invention is to provide a simple, economical, and effective arch supporter which can be attached to any 5 shoe and when so attached, the said supporter will not interfere in any way with the comfort of a pedestrian, and at the same time will materially aid in protecting the foot against strain.

Another object of my invention is the provision of an arch supporter provided with means whereby to properly position the supporting element upon the bottom of a shoe prior to permanently connecting the device 10 in position so that the supporter will be properly placed with respect to the sole and instep of the shoe before it is permanently attached.

A further advantage of the invention is that it will present the full supporting surface of the bottom of the shoe to the pedestrian and thus may, in effect, serve as a non-skid element.

Heretofore, so far as I am aware, various forms of arch supporters have been constructed to fit within the shoe or have been permanently built into the same, in which latter case flexibility of the shoe is materially impaired. In some instances, shoes fitted 25 with such arch supporters are uncomfortable, and in order to meet the added shoe area, parties using such removable supporters must use a shoe quite a little larger than a real fit. In other words, the last mentioned arch sup- 30 porter type is what might be termed a make-shift.

Furthermore, certain shoes have been made with a metallic spring arch support built within the sole, and it has been found that 35 these springs, under heavy load, will break down and the shoe in effect will flatten out at the arch. Where such springs are of sufficient strength to support the arch load, the same will cause the shoe to be so rigid that the ordinary flexing of the same in walking is not present.

With the above and other objects in view 40 which will appear hereinafter, the invention consists in certain peculiarities of construction and combination of parts substantially

as hereinafter described and more particularly defined by the appended claim, it being understood that such changes in the precise embodiment of the herein disclosed invention may be made as come within the scope of the 55 claim.

In the drawings, Figure 1 is a side elevation of a shoe illustrating my improved arch supporter attached thereto;

Figure 2 is a bottom plan view of the shoe 60 showing the relative position of the supporter with respect to the shoe;

Figure 3 is a detail transverse section through the supporter; and,

Figure 4 is a transverse sectional view on 65 the line 4—4 of Figure 2.

Referring more particularly to the drawings, it will be noted that I have described my improved arch supporter in connection with a shoe which comprises a heel portion 70 1 with the adjacent instep portion 2 and preferably the arch support is positioned in the instep adjacent the forward edge of the heel 1. The construction of a shoe usually includes the outer sole member 3, the inner 75 sole portion 4, and the sole lining 5.

Referring now more particularly to the drawings of the supporter itself, it will be noted that I have provided a metallic plate 6 which tapers in thickness from the forward edge, which is disposed at the portion of the instep 2, toward the back of the plate which is positioned adjacent the heel 1, thus taking care of the usual inclination of the instep 2 80 so that when the plate is attached to the instep, as shown in Figures 1 and 2, the lowermost portion thereof will be substantially parallel with the tread 7 of the front portion of the shoe and the tread of the heel. The lower side of the plate is provided with spaced 85 parallel outstanding flanges 8, said flange having under cut side portions 9 adapted to receive therein the flared edges 10 of the insert 11.

This insert 11 may be of a composition 90 of rubber, or the like, with the body portion thereof projecting beyond the lower faces of the flanges 8 when the device is in applied position, as shown in Figure 4 and the outer 95 or lower surface of the body 11 is so positioned as to have the same lie substantially 100

flush with the tread of the heel 1 and the tread 7 of the forward portion of the foot.

In the construction of shoes, it is apparent that the shape of the instep varies in shoes for men and women, women's shoes usually having the instep slightly curved transversely upon the outer surface thereof, while as a general rule, the instep of a man's shoe is nearly straight across and, therefore, the contacting surface of the plate 6 must necessarily conform to the outer surface of the instep in order to have the same fit snugly against the instep. In the present instance, I have illustrated the inner surface of the plate 6 as slightly curved to conform to the instep of a woman's shoe and certain types of men's shoes where the insteps are slightly curved. The side flanges of the plates 6 are tapered upwardly toward the body portion, as shown in Figure 4, and each side flange is provided with an opening to receive therethrough a securing rivet 12. These rivets 12 are first inserted through the sole portion 3 of the shoe with the tapering head part 13 embedded in the inner surface of the outer sole beneath the inner sole 4, as shown in Figure 4.

Preferably, the flanges 8 are slightly tapered, as shown at Figure 2, so that the insert when being placed in position is driven in between the flanges with the flaring portion 10 engaging beneath the undercut portion 9 of the flanges so as to securely retain the insert in position. Due to the elasticity of the insert, the frictional contact between the flanges and the flared portion of the insert will maintain the insert in proper position relative to the plate.

In order to save time and properly position the supporter with respect to the sole portion 40 of the shoe, and properly place the supporter within the instep, both the insert and the plate are provided with aligned openings 14 whereby a suitable pin or nail 15 can be passed through these openings and engaged with the sole portion 3, as shown in Figure 4. The plate 6 can then be adjusted so that the rivet openings therein can be readily aligned with the openings in the sole portion 3, so that the rivets 12 can be inserted in these openings 50 with the heads 16 for retaining the plate in position within the instep.

It is also preferred to provide a slightly hollow portion or recess portion 17 in the face of the plate which lies next to the sole portion 3, to provide for a certain amount of action on the part of the sole 3, when a person's weight is applied thereto.

It will be apparent from the foregoing that owing to the convenient arrangement of the arch supporter, it can be readily attached to any shoe without the aid of an expert, as the pin 15 can be properly centered between the side lines of the instep and at the proper distance from the heel 1, so that by adjusting the plate 6, the rivets 12 can be passed through

the proper openings for attaching the plate to the instep of the shoe.

While it is preferred to have the plate 6 formed of metal, it will be apparent that a suitable composition such as hard rubber, or the like, can be used if found desirable, and the plate as well as the instep can be made of different dimensions, the essential feature being that the ground engaging surface of the tread surface has a direct support for the article and, furthermore, attention is directed to the fact that when this article is attached to a shoe it does not impair the appearance of the shoe thereof.

It will be apparent that by utilizing an arch supporter of this general type, a positive and efficient support is formed for the foot under all conditions, and it has been found that users of this support can walk comparatively great distances without tiring and, it adds to the shoe the natural support which the foot should have under normal conditions.

While I have shown and described the arch supporter as an attachment to be applied to the under side of the instep of the shoe sole, obviously under certain conditions the support can be made integral with the shoe or it may be provided as a portion of the heel.

I claim:

An external arch supporter for shoes comprising a solid attaching plate having a concavity on its upper face and a longitudinal dovetail groove on its lower face, means for securing the plate on opposite sides of the groove to the instep of a shoe forwardly of the heel, a resilient insert having its upper end shaped to correspond to the groove and slidably mounted therein, the insert and the plate having openings for registration with one another when the insert is in its operative position in the groove, and means received in said openings for holding the insert normally against movement.

In testimony that I claim the foregoing I have hereunto set my hand at Milwaukee, in the county of Milwaukee and State of Wisconsin.
